CLAIM

The ornamental design for an pair of outsoles for a woman's shoes, as shown and described.

DESCRIPTION

FIG. 1 is a perspective view of the left odd of a pair of outsoles for a woman's shoes showing my new design; the right odd is a mirror image, and the broken lines showing the remainder of the shoe illustrate the portion of the design that forms no part of the claim;

FIG. 2 is a front elevation view thereof, the view for the right foot being a mirror image;

FIG. 3 is a rear elevation view thereof, the view for the right foot being a mirror image;

FIG. 4 is a left side elevation view thereof, the view for the right foot being a mirror image;

FIG. 5 is a right side elevation view thereof, the view for the right foot being a mirror image; and,

FIG. 6 is a bottom plan view thereof, the view for the right foot being a mirror image.
